(57) **CLAIM**

The ornamental design for an inflatable baby bottle, as shown and described.

DESCRIPTION

FIG. 1 is a top, front, left perspective view of the inflatable baby bottle, showing in a first configuration and expanded for clarity of disclosure;

FIG. 2 is a top, front, right perspective view of FIG. 1, shown compact in a second configuration;

FIG. 3 is a top plan view thereof;

FIG. 4 is a bottom plan view thereof; and,

FIG. 5 is a front elevation view of the inflatable baby bottle shown in condition of use, the rear elevation view being a mirror image thereof.

In the drawings, the broken lines depict portions of the inflatable baby bottle that form no part of the claimed design. In FIG. 5, the broken lines showing a bottle cap depict environmental subject matter and form no part of the claimed design.

All broken lines form no part of the claim.
